UNITED STATES PATENT OFFICE.

GEORGE B. SNYDER, OF WILMERDING, PENNSYLVANIA.

LOCK.

1,037,072.

Specification of Letters Patent.

Patented Aug. 27, 1912.

Application filed July 9, 1912. Serial No. 708,398.

To all whom it may concern:

Be it known that I, GEORGE B. SNYDER, a citizen of the United States of America, residing at Wilmerding, in the county of Allegheny and State of Pennsylvania, have invented certain new and useful Improvements in Locks, of which the following is a specification, reference being had therein to the accompanying drawing.

10 This invention relates to locks in a manner as hereinafter set forth and more particularly to a key operated lock that has been especially designed for use in connection with milk cans, particularly of the large size employed for shipping milk, cream, and other liquids; although the principle of the invention with certain modification may be applied to various kinds of receptacles.

15 The primary object of the invention is to provide a key actuated lock in a manner as hereinafter set forth for milk cans adapted to prevent the can from being surreptitiously opened and the contents thereof tampered with or wholly or partially removed during the transportation of the milk can from the producer to the consumer.

20 A further object of the invention is to furnish a milk can with a lock that is concealed, that cannot be tampered with, that is simple in construction, strong and durable, and efficient as means for locking a lid or closure upon a receptacle.

25 It is to meet and overcome these difficulties that my invention is primarily directed, and with this understanding of the gist of the invention, references will now be had to the drawing, wherein:

Figure 1 is a front elevation of a portion of a milk can provided with a lock. Fig. 2 is an enlarged longitudinal sectional view of the lock in a locked position. Fig. 3 is a similar view of the lock showing the lock in an unlocked position. Fig. 4 is a front elevation of the lock. Fig. 5 is a cross sectional view of a portion of the same. Fig. 6 is a plan of the key used in connection with the lock. Fig. 7 is an end view of the key.

30 The reference numeral 1 denotes the neck of a can or other receptacle and the front side of the neck 1 is provided with an opening 2. This opening 2 is adapted to register with an annular groove 3 formed in the wall of the lid or closure 4 placed in the neck 1 of the receptacle, the annular groove 3 being formed by an inwardly pro-

jecting portion of the lid or closure and said groove having a flat bottom wall and a beveled or inclined top wall, as best shown in Figs. 2 and 3.

35 Riveted or otherwise connected to the front side of the neck 1, as at 5 is the face plate 6 of a cylindrical lock body 7. The cylindrical lock body 7 has a longitudinal bore 8 with the outer end of said bore reduced, as at 9 and the inner end thereof enlarged to provide an annular seat 10 for the peripheral flange 11 of a bushing 12 that is fitted in the inner end of the bore 8. The bushing 12 registers with the opening 2 in the can neck 1 and said bushing has a longitudinal slot 13, the purpose of which will presently appear.

40 Slidably and rotatably mounted in the reduced end 9 of the bore 8 is a cylindrical bolt 14 provided intermediate the ends thereof with a collar 15. The inner end of the bolt 14 terminates in a beveled tooth 16 having a radially disposed lug 17. The outer end of the bolt 14 is provided with a shank 18 having a cross head 19. Encircling the bolt 14, between the collar 15 and the outer end of the bore 8 is a coiled compression spring 20 and the tension of this spring is sufficient to shift the bolt 14 to a locked position, when the lug 17 alines with the slot 13 of the bushing 12.

45 The reference numeral 21 denotes a key having the shank 22 thereof provided with a transverse slot 23 and the walls of said slot are recessed, as at 24 to receive the cross head 19 of the shank 18. By placing the key in engagement with the shank 18 of the bolt 14, as best shown in Fig. 2, the key can be partially rotated whereby the cross head 19 will engage in the recesses 24. By pulling outwardly upon the key 21, the coiled compression spring 20 can be placed under tension and the lug 17 shifted to the outer end of the bushing 12 and then the bolt 14 partially rotated whereby the lug 17 will engage the outer end of the bushing 12. The tooth 16 of the bolt is therefore retracted and the end of said tooth is within the opening 2 of the neck 1, whereby the lid 10 or closure of the can can be easily and quickly removed from the neck 1.

50 When the bolt 14 is rotated by the key to place the lug 17 in alinement with the slot 13 of the bushing 12, the tension of the spring 20 is sufficient to force the bolt inwardly toward the neck 1, placing the tooth

16 of the bolt in the groove 3 of the lid or closure, thereby preventing the lid or closure from being removed from the neck 1. The lid or closure can be placed in the 5 neck 1 of the receptacle without resorting to the use of the key, as the bolt 14 recedes until the lid or closure is seated, when said bolt engages in the groove 3 and locks the lid or closure.

10 What I claim is:—

In a lock, the combination with a receptacle, and a lid adapted to fit in said receptacle and having an annular groove formed therein, of a lock body carried by 15 said receptacle and having a longitudinal bore formed therein, a bushing seated in the inner end of the bore of said body and having a longitudinal slot formed therein, a bolt 20 slidably mounted in the bore of said lock body and having a beveled tooth end ex-

tending through said bushing and adapted to engage in the groove of said lid, a lug carried by the inner end of said bolt and adapted to engage the outer end of said bushing to retain said bolt in a retracted 25 position, a coiled compression spring encircling said bolt within the bore of said body and adapted to hold said bolt in a locked position, and a shank carried by the outer end of said bolt and having a cross head adapted to be engaged by a key whereby said bolt can be manually shifted and rotated.

In testimony whereof I affix my signature in the presence of two witnesses.

GEORGE B. SNYDER.
